UNITED STATES PATENT OFFICE

JOSEPH W. HELDRETH, OF WYTHEVILLE, VIRGINIA.

RAIL JOINT.

Application filed June 27, 1921. Serial No. 480,745.

To all whom it may concern:

Be it known that I, JOSEPH W. HELDRETH, a citizen of the United States, residing at Wytheville, in the county of Wythe and State of Virginia, have invented a new and useful Rail Joint, of which the following is a specification.

This invention relates to rail joints, one of its objects being to provide a coupling which will hold the rails properly assembled without requiring the use of bolts extending through the rails as heretofore and which will properly support the rails at their meeting ends so that they will not sag and cause the car wheels to pound while passing thereover.

Another object is to provide a joint made of separable parts so that the rails can be removed either longitudinally or laterally as preferred.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

Figure 1 is a side elevation of a rail joint constituting the present invention.

Figure 2 is a section on line 2—2, Figure 1.

Figure 3 is a section on line 3—3, Figure 1.

Figure 4 is a view similar to Figure 3 but showing a modified structure.

Referring to the figures by characters of reference 1 designates one member of the joint, the same being formed with a base 2 having openings 3 for receiving spikes or other fastening devices. The lower portion of the inner or upstanding side of this member is so shaped as to follow the configuration of one side of the base of a rail, this curved overhanging portion being indicated at 4 in Figure 3. The upper portion of the inner side of the member 1 is so shaped, as shown at 5, as to fit snugly against one side and the bottom of the head of a rail and arranged between the portions 4 and 5 of the member 1 is a longitudinal extension 6 the thickness of which is substantially equal to the thickness of the webs of the rails. This extension does not lie flush with the sides of the member 1 but terminates inwardly therefrom so as to provide recesses 7 at the ends of the extension. A dove-tail rib 8 is formed longitudinally along the side of the extension.

The other member 9 of the joint has an extension 10 upon the base thereof similar to the extension 2 and the inner portion of this member has its lower surface shaped to conform with the contour of the inner flange of the base of a rail, as shown at 11. The top of this overhanging or inner portion of the member 9 is adapted to extend under the head of a rail and to engage said head. A dove-tail groove 12 is provided on the inner surface of the overhanging extension and is so proportioned as to receive the dove-tail rib 8 when the two members 1 and 9 are placed in proper relation to each other and shifted longitudinally relative to each other.

The rails to be coupled have been indicated at R and the webs R' are cut away at their ends so that when the rails are assembled end to end there will be sufficient space between the webs to allow the extension 6 to rest therein.

In using the coupling the member 1 is fastened in position and the rails are then placed laterally against said member so that their base flanges will lie under the overhanging portion 4 and the extension 6 will be supported between the webs. The other member 9 is then shifted longitudinally into engagement with the rib 8 and when the member 9 is brought to proper position it is also fastened and the rails will thus be securely held. If preferred the two members of the coupling can first be assembled and fastened and the rails inserted longitudinally between them but this is not always possible or desirable and for this reason the coupling has been formed of two parts. It is to be understood that instead of making the coupling in two interfitting parts as heretofore described it can be made in one piece as shown in Figure 4. In this case the extension 13 is made integral with both members of the coupling and the rails, consequently, can only be assembled with the coupling by inserting them longitudinally into opposite sides of the coupling.

What is claimed is:—

In a rail joint a member having a longitudinal dove-tail groove in one face and open at both ends, a second member, a longitudinal extension thereon terminating inwardly from the ends of said second member for abutment against the grooved member, a dove-tail rib on the extension and extended throughout the length thereof, said 10 rib being shiftable longitudinally into the groove to hold the members assembled in contact, and rails having slots in the end portions thereof, said rails being slideable longitudinally toward each other to receive 15 the extension within the slots in the rails

said members being undercut to receive the base flanges of the rails, there being apertures extending through the members for the reception of tie engaging fastening means, the bottom faces of the members 20 adapted to rest upon the tie supporting the rails.

In testimony that I claim the foregoing as my own, I have hereto affixed my signature in the presence of two witnesses.

JOSEPH W. HELDRETH.
